UNITED STATES PATENT OFFICE.

ISADORE F. PFEIFFER, OF ALTOONA, PENNSYLVANIA.

PISTON RING.

Application filed November 3, 1924. Serial No. 747,610.

This invention relates to improvements in piston rings, the general object of the invention being to make the ring and groove of spiral shape so that the ring can be 5 screwed onto the piston without expanding the ring.

Another object of the invention is to provide means for holding the ring in the groove and to bridge a portion of the spiral 10 space formed by the convolutions of the ring.

This invention also consists in certain other features of construction and in the combination and arrangement of the several parts, to be hereinafter fully described, 15 illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view of a piston showing my 25 improved ring thereon.

Figure 2 is a section on line 2—2 of Figure 1.

Figure 3 is a top plan view with a part 30 broken away.

Figure 4 is a section on line 4—4 of Figure 1.

Figure 5 is a view of the ring itself.

Fig. 6 is a view of a modification.

Figure 7 is a section on line 7—7 of Figure 6.

Figure 8 is a fragmentary edge view.

Figure 9 is a diagrammatic view of the ring.

As shown in these views, I form a spiral 40 groove in the piston A, the groove starting at the top of the piston and extending to a point adjacent the skirt of the piston so that the groove is of considerable length. The ring 2 is also of spiral shape and the ring is adapted to be placed in the groove by a rotary or screwing motion so that it is not necessary to expand the ring over the piston as is now done with the split rings. Thus the ring is not distorted in putting it on the 45 piston. After the ring is in place a pin 3 is placed in the upper part of the groove to prevent the ring from working out of the groove if the ring should break. The ring is held in place and the space bridged by means of a plug 4 arranged in a recess 5

formed in the piston and having grooves in its head to receive the lower end of the ring and a part of one of the convolutions thereof. This plug projects sufficiently to fill the space between the lower end of the ring and the next convolution thereof. The ring is locked to the plug by means of a pin 6 which passes through the plug and through a recess 7 formed in the lower end of the ring. Figures 6, 7 and 8 show the invention applied to a steam piston, the ring being shown at 1' and the piston at A'. In this case a wedge member 7 is driven into a dove-tail slot 8 formed in one wall of the piston, the wedge member having grooves 9 therein to receive the ring, the outside grooves being the same width as those in the piston, while the center groove 9' in the wedge, is less in width so as to receive, and hold tightly, the reduced portion 10 of the piston ring. This 60 arrangement will prevent leakage between the ring and walls of the spiral groove as the groove in the piston is made slightly larger than this ring so as to permit expansion and contraction of the ring but the reduced part 10 and the small groove 9' in the wedge member being arranged at the center, together with the weight of the piston acting downward, which effects a snug fitting joint between the inside face of rings and bottom of grooves in wedge, thereby effectively preventing leakage through the space between the ring and walls of the groove from either side of the piston. This 65 arrangement of parts is clearly shown in Figure 8.

This form of ring will give high compression, the cylinder will wear round as the ring pressure is uniform, there is no danger of distorting the ring in putting it in place, 70 the ring can be made thicker which adds strength to it without interfering with its application and the ring is not liable to break as the split rings now in use. The stop pin and wedge member not only hold the ring in place but also prevent leakage through the spiral space formed by the ring. In the locomotive application, the live steam entering the cylinder will carry oil around the spiral up to the wedge member, thereby 75 oiling the cylinder walls ahead of the piston travel instead of oiling the walls after exhaust, as is now done.

The cycle in applying the steam ring is as 80 follows: The ring is screwed in position 110

and the ring is then pulled away from the wedge receptacle, (this can be easily done because of the eccentricity of the groove), the wedge is driven in the piston—and then the ring, at the reduced section is driven home in the wedge.

Pistons using other style rings, that are of a design that will allow them to be reduced in diameter, can be so reduced, and a ¹⁰ ring having within it a spiral groove, can be shrunk or otherwise fastened to the old piston, to allow the use of the spiral ring.

It is thought from the foregoing description that the advantages and novel features ¹⁵ of my invention will be readily apparent.

I desire it to be understood that I may make changes in the construction and in the combination and arrangement of the several parts, provided that such changes fall within the scope of the appended claim.

What I claim is:—

In combination with a piston having a spiral groove in its circumference which starts at the top of the piston, a spiral ring formed in one piece and fitting in the groove, said ring being adapted to be threaded in the groove by placing its lower end in the top part of the groove and giving it a rotary movement, said piston having a recess therein which communicates with several convolutions of the groove, a member fitting in said recess and having grooves therein receiving portions of a number of spirals of the ring for holding the ring in place and preventing leakage through the space formed by the ring and means for connecting the ring with the member.

In testimony whereof I affix my signature.

ISADORE F. PFEIFFER.
